UNITED STATES PATENT OFFICE.

LÉON MICHA, OF ANTWERP, BELGIUM.

ELASTIC WHEEL.

1,426,587.

Specification of Letters Patent. Patented Aug. 22, 1922.

Application filed November 27, 1914. Serial No. 874,277.

To all whom it may concern:

Be it known that I, LÉON MICHA, a subject of the King of the Belgians, residing at Antwerp, Belgium, have invented new 5 and useful Improvements in Elastic Wheels, of which the following is a specification.

The present invention has for its object an elastic wheel, which, having the properties and advantages of pneumatic tyres, 10 is suitable to take the place of such tyres on vehicles.

Many attempts have already been made to provide a substitute for pneumatic tyres, in order to avoid all inconveniences connected 15 with the use of same, such as for instance the bursting or the tearing or wearing of the cover, or the risks of the same becoming punctured, and the like.

Most of the known constructions intended 20 to replace pneumatic tyres require the use of springs of different shapes and varieties; all these constructions, however have the great disadvantage that the springs are liable to rupture and to irregularities in 25 their operation.

The object of my present invention is a wheel which avoids and removes these drawbacks connected with pneumatic tyres; the characteristic feature of my said invention 30 consists therein, that the elastic tyre is disposed on a frame-work, allowing the same to keep its circular shape, and to remain substantially concentric with respect to the felloe of the wheel in various circumstances.

To this end, the elastic tyre, put on the felloe of the wheel is held on the same concentrically by means of a metallic frame-work. The said frame-work comprises a plurality of inclinable frames extending between 35 the felloe and tyre each at an angle to the corresponding radius of the wheel, said frames each having one end pivotally connected to the felloe and the other end pivotally connected to the tyre, while the extent of the movement or travel of said frames in relation to the felloe may be limited by pins or any other suitable means.

This construction shows all the characteristic features of the pneumatic tyre, and 50 offers besides the advantages of simplicity. In the accompanying drawings one mode of execution of my invention is represented:

Fig. 1 is a radial section through the periphery of the improved elastic wheel. 55 Fig. 2 is a diagrammatic elevation of the said wheel.

In the drawing *a* designates a wheel of any suitable construction, the felloe *b* of which carries an elastic, compressible tyre *g* of which the inner diameter is larger than 60 the outer diameter of said felloe, and which is maintained in position in relation to the latter by means of a number of inclinable frames *c* each comprising a pair of links *e* pivotally connected at one end to the felloe *b* by means of a pin *d* and at the other end to the tyre *g* by means of a pin *f*.

These frames *c* are spaced from each other at such distance as to ensure to the tyre *g* its circular shape and to secure the 70 same concentrically in relation to the felloe *b*; but owing to the disposition of the pins *h*, they are at the same time subjected to an inclination in relation to the direction of the spokes of the wheel; and the wheel is 75 owing to this arrangement suspended in the tyre.

The aforesaid pins *h* may be adapted to form suitable abutments to limit the inclination of the frames *c*.

Washers *p* and *r* are inserted between the sides of the tyre *g* and of the felloe *b* respectively and the adjacent ends of the links *e*, and if desired a second and thinner washer may be inserted between each washer 85 *p*, *r* and said ends of the links *e*. This arrangement makes it possible by oiling or lubricating only the contacting surfaces of this thinner washer and the washers *p*, *r* and the ends of the links *e*, to obtain a good 90 lubrication of the connections at the ends of said links *e* without having a greasy surface in contact with the material of the tyre *g*.

The effect obtained by the above described 95 arrangement is the following:

The tyre *g*, which is in contact with the road, shows a tendency to move towards the centre of the wheel, while the frame-work *c* adjacent the point of contact with 100 the road will take a strongly inclined position in relation to the spokes.

The other frames will more or less follow this tendency of inclination, and the circumference, and therefore the diameter of 105 the circle formed by the elastic band *g* will decrease, and every point of the elastic tyre will be compressed in itself between each one of the successive frames *c* and the next.

The same movement of parts and the same 110 effect is naturally attained, if the wheel meets some obstacle on its way.

In such a case the inclinable frame which is nearest the road surface will take a still more inclined position, whereby a further and stronger circumferential contraction of 5 the compressible tyre will be caused.

The obstacle having been passed, the elasticity of the tyre will cause a circumferential expansion of the latter, equal to its contraction on meeting the obstacle, to 10 take place, and the frames *c*, leaving the still more inclined position referred to above, will return to their normal inclined position.

Practical experience has shown that the circumferential contraction or compression 15 exercised upon the tyre is not uniform on the whole length of the circumference of the said tyre nor on the totality of its periphery, and that the greatest compression takes place in the neighborhood of the 20 point where the power which produces the deformation is exerted. It has further been found that at the point situated at the opposite end of the diameter an easy temporary deformation of the tyre is produced, 25 but that the tyre immediately regains its circular shape.

The construction illustrated may be varied in any convenient way, especially as far as the construction of the frame-work, the 30 pins limiting the inclination of the frames, and the pivotal connection of the latter to the felloe of the wheel or their connection to the elastic tyre are concerned.

The elastic tyre itself may be carried out

in every suitable form or shape of cross 35 section, and may also be disposed in any suitable manner.

I claim:

1. In an elastic wheel, an elastic tyre spaced from the felloe of the wheel, in combination with a plurality of inclinable frames extending between the said felloe and the said elastic tyre each at an angle to the corresponding radius, and pivotal connections between the felloe and the rim portion of the tyre and the respectively adjacent ends of the aforesaid frames, substantially as described.

2. In an elastic wheel, an elastic tyre spaced from the felloe of the wheel, in combination with a plurality of inclinable frames extending between the said felloe and the said elastic tyre each at an angle to the corresponding radius, pivotal connections between the felloe and the rim portion of the 55 tyre and the respectively adjacent ends of the inclinable frames, and abutment pins secured on the felloe and adapted to set the initial inclination of the said frames and to limit the amplitude of their movement, substantially as described.

In testimony whereof I affix my signature in presence of two witnesses.

LÉON MICHA.
